STERILIZER RACK

Harlan F. Borin, Chicago, Ill., assignor to American Hospital Supply Corporation, Evanston, Ill., a corporation of Illinois

Application April 29, 1954, Serial No. 30,241

Term of patent 14 years

(Cl. D44—29)

Fig. 1 is a top plan view of a sterilizer rack showing my new design;

Fig. 2 is a side elevational view thereof;

Fig. 3 is a bottom plan view thereof; and

Fig. 4 is an end elevational view thereof.

I claim:

The ornamental design for a sterilizer rack, as shown.
